DESIGN FOR A DRESS

Fannie Sussman, New York, N. Y.

Application August 6, 1937, Serial No. 70,870

Term of patent 3½ years

To all whom it may concern:

Be it known that I, Fannie Sussman, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the specific embroidery on the waist portion of the one piece dress as shown, and which embroidery gives a two piece appearance to the dress.

I claim:

The ornamental design for a dress substantially as shown and described.

FANNIE SUSSMAN.
